Joseph Stewart, of Baltimore, Md.
(Assignor to Wm. S. Stuart, & Peterson, of Baltimore, aforesaid)
Letters Patent No 681. December 5, 1854

The Schedule referred to in these Letters Patent and making
part of the same

To all to whom these presents shall come

Be it known that I, Joseph Stewart, of Baltimore in the county of Baltimore
and state of Maryland have invented a new Design for Stoves and that the
following is a full clear and exact description of the principle or character
which distinguishes it from all other things before known and of the usual
manner of making, modifying and using the same reference being had
to the accompanying drawings

Fig. 1. - Is a view of the side of the stove illustrating
the design thereof

Fig. 2. - Is a view of the back of the stove illustrating
the design thereof

Fig. 3. - Is a view of the hearth plate of the stove
illustrating the design thereof.
